UNITED STATES PATENT OFFICE.

HARRY C. BUHOUP, OF CHICAGO, ILLINOIS.

COUPLING-RELEASE RIGGING.

1,162,333.

Specification of Letters Patent.

Patented Nov. 30, 1915.

Application filed April 16, 1914. Serial No. 832,213.

To all whom it may concern:

Be it known that I, HARRY C. BUHOUP, a citizen of the United States, residing at Chicago, in the county of Cook and State of Illinois, have invented certain new and useful Improvements in Coupling-Release Rigging; and I do hereby declare the following to be a full, clear, and exact description of the invention, such as will enable others skilled in the art to which it appertains to make and use the same.

My invention relates to the construction of that class of devices or mechanism, commonly termed release rigging, which are employed for actuating the locking mechanism of car couplers to release or unlock the coupler knuckle so as to permit it to rotate to open position.

It is the purpose of my invention to provide a form of coupler release rigging which is simple, durable, cheap and efficient, which may operate to automatically unlock the knuckle in case the connection of the coupler with the car is disrupted, which may be quickly and readily locked in a position in which it is adapted to retain the coupler locking mechanism in unlocked position, and which may be conveniently actuated either by the hand or foot of the trainman. These several objects are accomplished by the means hereinafter described and particularly pointed out in the appended claims defining the scope of my invention.

In the drawings illustrating the best modes in which I contemplate applying my invention, Figure 1 is a plan view of a coupler release rigging embodying my invention, showing its relation to a coupler and the end of a car. Fig. 2 is a front elevation of the construction shown in Fig. 1. Fig. 3 is a side elevation of the construction shown in Figs. 1 and 2. Fig. 4 is a sectional view taken in the plane of the line 4—4, Fig. 1. Fig. 5 is a detail view taken in the plane of the line 4—4, Fig. 1, showing the position assumed by the uncoupling lever when the coupler is locked. Fig. 6 is a detail view corresponding to Fig. 5, but illustrating the position assumed by the uncoupling lever when the coupler is unlocked. Fig. 7 is a detail front elevation of the devices illustrated in Figs. 5 and 6, the parts being in the relative positions shown in Fig. 5. Fig. 8 is a view corresponding to Fig. 4, but illustrating a modified construction wherein the uncoupling lever is mounted beneath the end

of the car; and Fig. 9 is a detail plan view illustrating a modification of my invention in which the uncoupling lever is formed in one piece.

I will now proceed to describe my invention more fully, so that others skilled in the art to which it appertains may apply the same.

The car body is indicated generally by 60 the reference numeral 1; 2 is the coupler and 3 is its locking device.

Mounted upon the end of the car, and preferably secured to and projecting outwardly from the end sill 4 thereof, are two 65 brackets 5 and 6, respectively, which are designed to receive and permit the rotation of a transversely extending uncoupling lever 7. If desired, however, and as shown at 5^a in Fig. 8, the supporting brackets for the 70 uncoupling lever 7 may project downwardly so that the uncoupling lever may be located beneath the end sill 4 instead of in front of it. The opening in each of these brackets for the reception of the uncoupling lever 7 75 extends farther forward at the bottom than at the top, or is wider at the bottom than at the top, such construction being for the purpose of permitting the lever to automatically rotate and thereby unlock the 80 coupler should the connection of the latter with the car be disrupted. This automatic unlocking rotation of the uncoupling lever 7 is effected in the following manner: When 85

the coupler 2 moves forward after breaking 90 its draft connections the lever 7, being connected to the coupler lock 3, is carried forward and its upper forward edge 7^a is thus brought into contact with the upper portion 95 of the forward, inner wall of one or more of the brackets 5 and 6. The upper edge of the uncoupling lever being thus arrested, the continued forward movement of the coupler 2 causes the lever 7 to rotate upwardly to 100 unlocked position around its edge 7^a as an 105 axis, the increased width of base of the opening through the supporting brackets permitting the lower portion of the uncoupling lever to swing upwardly and outwardly, as will be readily understood from an inspection of Fig. 6. By thus automatically causing the uncoupling lever to raise the lock 3 of the coupler, the coupler 2 is released from its mate and is prevented from being wholly disengaged from the car and dropping to 110 the track.

As it is at times desirable to lock the un-

coupling lever 7 in a position corresponding to the unlocked position of the coupler lock 3, it is preferred to provide the bracket 5 or 5^a, as the case may be, with a laterally projecting tooth or locking lug 8 which extends in the direction of length of the uncoupling lever and which is adapted to supportingly engage a corresponding tooth or lug 9 with which the uncoupling lever 7 is provided. As more particularly shown in Figs. 2 and 7, the tooth 9 is preferably formed as an integral part of a collar 10 that is riveted or otherwise rigidly secured to the uncoupling lever. The latter is capable of sliding through its supporting brackets in the direction of its length sufficiently far to permit the under face of the tooth 9 to be brought into engagement with, and to be disengaged from the upper face of the tooth 8, thus enabling the uncoupling lever to be quickly locked in uncoupling position and quickly released from such locked position.

In order to render it impossible for the teeth 8 and 9 to prevent an uncoupling rotation of the uncoupling lever 7, the under face of the tooth 8 and the upper face of the tooth 9 are correspondingly inclined, as well shown in Fig. 7, such construction permitting the tooth 9 to easily ride over the tooth 8 when the lever 7 is rotated upwardly.

The uncoupling lever 7 is preferably formed in two sections, the portion 7^b which passes through the supporting brackets being preferably rectangular in cross-section and the portion 7^c adjacent to the coupler 2 being preferably a round bar. Between the inner bracket 6 and the coupler 2 the section 7^b of the uncoupling lever is formed with an upwardly and forwardly extending crank portion the forwardly projecting end whereof is slotted, as at 7^d, to receive the lock engaging section 7^e of the uncoupling lever and to permit the latter to oscillate back and forth with respect to the section 7^b sufficiently far to accommodate itself to the normal longitudinal movements of the coupler 2. The inner end 7^e of the lock engaging section of the uncoupling bar preferably extends at right angles to the body of the section 7^c and passes through an appropriately formed hole 7^f in the lever section 7^b, the hole 7^f being sufficiently large to permit the play or oscillation of the section 7^c in the slot 7^d, and a cotter 7^g being employed to maintain the integrity of the connection of the lever sections 7^b and 7^c. This construction, it will be noted, is of great advantage, as new couplers or coupler locks may be readily substituted for old or broken ones without the necessity of disturbing the principal section 7^b of the uncoupling lever, all that is necessary to do being to withdraw the cotter 7^g and then remove and replace the lock engaging section 7^e of the uncoupling lever. As shown in Fig. 9, however,

an uncoupling lever 11 formed in a single piece may be employed if desired, the coupler lock 3 being, in such case, preferably actuated through the intermediacy of a bolt 12 which extends through an elongated slot 11^a in the forwardly extending end of the lever 11.

The operating handle 7^h of the uncoupling lever is preferably formed as a separate member which hooks over the outer end of 75 the section 7^b of the uncoupling lever and is riveted thereto. As shown more especially in Fig. 3, it is also preferred to provide the uncoupling lever 7 with an operating pedal 7ⁱ which extends behind the sill-step 13 in a position permitting it to be conveniently pressed downward by the foot of a trainman while standing on the step. It is, as shown, most convenient to form the operating lever 7^h and the operating pedal 7ⁱ 85 from a single bar of metal, as the same means thereby suffices to rigidly secure both to the outer section 7^b of the uncoupling lever 7.

I claim:

1. In a coupler release rigging, the combination of an uncoupling lever having a portion of angular cross section, and a bracket therefor, said bracket having an aperture for the reception of the said angular 95 portion of the uncoupling lever and having a surface bounding said aperture which is adapted to be engaged by the upper edge of the uncoupling lever, whereby the lever is caused to rotate automatically upon its upper edge as an axis to effect an emergency release.

2. In a coupler release rigging, the combination with a rotatable uncoupling lever which is provided with a portion that is of 105 angular cross-section, of a bracket for supporting said uncoupling lever and in which said lever is rotatable, said bracket being formed with an aperture through which the uncoupling lever extends, and said aperture 110 having its forward wall inclined outwardly and downwardly to constitute means for arresting forward movement of the upper portion of said uncoupling lever and for permitting the lower portion of said lever to 115 swing upwardly and forwardly.

3. In a coupler release rigging, the combination of means for movably supporting an uncoupling lever, and an uncoupling lever comprised of a plurality of sections, one of said sections having a crank formed with a longitudinally extending portion and with an outwardly extending portion having a slot therein and the other of said sections being pivotally connected to the longitudinally extending portion of said crank and extending through said slot.

4. In a coupler release rigging, the combination of means for movably supporting an uncoupling lever, and a rotatable uncou- 130

pling lever comprised of a plurality of connected sections one of which is formed with a crank portion, each of said sections having its connected end bent at an angle to the axis of rotation of the section, and one of said bent ends having a slot through which the connected section passes, said last named section being pivotally connected by its bent

end to the crank portion of the section having the slot. 10

In testimony whereof I affix my signature, in the presence of two subscribing witnesses.

HARRY C. BUHOUP.
